HENRY F. HOLKENBRINK, OF PORTLAND, OREGON

BRUSH CONTACT SWITCH

Application filed August 13, 1928. Serial No. 299,302.

This invention relates generally to switches ordinarily employed to control an entire lighting or power circuit, with special reference to switches having brush contacts and means for rapidly separating such contacts.

The main object of this invention is to provide a special form of switch and mounting therefor which will be exceedingly compact in its construction and which will provide a central insulation completely separating the two sides of the switch.

The second object is to provide an improved toggling arrangement for the purpose of securing a smoother action for the operating lever.

The third object is to so construct the switch as to provide more and better guides for the moving parts.

The fourth object is to so construct the switch and its mounting, especially its brush contacts, that it may be very easily manufactured.

The fifth object is to so construct the device that it may be well adapted for use in batteries of any number of switches, due to the fact that not only are the sides of the switch separated from each other and from the fuse compartment but that the switch itself is completely enclosed in suitable insulation.

These, and other objects, will become more apparent from the specification following as illustrated in the accompanying drawings, in which:

Figure 1 is a plan showing three of the devices mounted side by side in a battery. Figure 2 is a section taken along the line 2—2 in Figure 1. Figure 3 is a section taken along the line 3—3 in Figure 1. Figure 4 is a section taken along the lines 4—4 in Figure 3. Figure 5 is a perspective detail of the bracket and guide rods. Figure 6 is a perspective detail of the slide and contact holder rods. Figure 7 is a section taken along the line 7—7 in Figure 1 with parts broken away and in the upward position. Figure 8 is a view similar to Figure 7 but in the downward position. Figure 9 is a diagram of the toggle showing the throw handle in position to trip. Figure 10 is a fragmentary side ele-

vation of a contact brush end showing its manner of contacting with a contact bar.

Similar numbers of reference refer to similar parts throughout the several views.

Referring in detail to the drawings, the device itself is mounted upon a molded base 10 having the longitudinal side walls 11 and the intermediate dividing wall 12. The walls 11 and 12 are joined by a cross wall 13. The walls 11 and 12 slope toward one end of the base 10, which carries the terminals 14 and 15 for the fuses 16. Holes 17 and 18 are provided for fastening screws. Contact bars 19 extend from the terminals 15 through the wall 13 and are provided with downwardly sloping ends 20 which extend into a recess 21 in the base 10. It is desirable to provide cut-out portions 22 in the walls 11 and 12 for the purpose of providing better access to the fuses 16. Contact bars 23, similar to the bars 19, also project into the recess 21 and connect with the terminals 24, which are held in position by the knurled nuts 25.

Mounted on the middle wall 12 are the stud bolts 26 between which the top side 27 of the wall 12 is cut away to provide clearance for the switch parts. A cover plate 28 extends across the opposite walls 11 between the stud bolts 26, and is held down thereby. The cover plate 28 is provided with an upwardly bulging middle portion 29 to whose under side is secured a bracket 31 by means of the screws 30. The edges 32 of the bracket 31 are flanged outwardly and provided with holes 33 for the reception of the screws 30. The bracket 31 is provided with a pair of guide rods 34 which extend through the member 29. The closed side 35 of the bracket 31 is provided with holes 36 for the reception of the contact holder rods about to be described.

In the bracket 31 is placed a channel-shaped slide 37 in which are mounted the contact holder rods 38 whose opposite ends 39 are shouldered and threaded. The rods 38 pass through the holes 36 in the bracket 31. The slide 37 is also provided with a pair of holes 40 which provide clearance for a spring. On the slide 37 is secured a U-shaped extension 41 having the laterally turned ears 42

provided with holes 43 which also receive the rods 34.

On the shouldered ends 39 of the rods 38 are mounted the contact brushes 44, preferably of laminated copper, whose central portion 45 is beveled at the ends 46 to match the ends 20 of the contact bars 19. The upper pair of leaves 47 are somewhat longer than the leaves having the angled ends 46, and one of the longer leaves is provided at each end with an arcing point 48, preferably of heavy metal crimped upon the lighter material of the spring leaf 47. Insulating washers 49 and 50 of ample size and thickness are provided above and below the spring leaves of the brush and are held in place by the nuts 51 on the shouldered ends 39.

It will be understood that there are two complete sets of brushes, namely one on each pair of rods 38. A spring 52 is placed on each guide rod 34 and passes freely through the hole 40 and bears against the under side of the ears 42. The function of the springs is to normally urge the brush members out of contact, or toward the cover plate 28.

Above the cover plate 28 is mounted a U-shaped standard 53 which is secured to the side 27 by means of the screws 54. The standard 53 is provided with the out-turned ears 55 which receive the ends of the rods 34. Between the sides of the standards 53 is mounted an operating lever 56 on a pivot 57 which journals in the sides of the standards 53. On the lever 56 is formed a projection 58 which carries the laterally projecting stud 59. On each side of the lever 56 is mounted a toggle operating arm 60, also mounted on the pivot 57. Between the ends of the member 60 is attached the end of a bell crank lever 61 by means of a rivet 62. The pivot 63 of the bell crank lever 61 is mounted in the holes 64 in the extension 41 of the contact holder slide 37.

The arm 65 of the bell crank lever 61 acts as a stop for the toggling position of the lever 61 by contacting with the edge 66 of the slide 37. Shock absorbing rubber blocks 67 are mounted on the guide rods 34 between the ears 42 and 55. A housing 68 is secured to the top of the side 27 by means of the screws 69. A handle 70 is provided on the end of the lever 56 after the housing 68 is put into position. The housing 68 is provided with a slot 71 to permit the free movement of the lever 56.

It will be observed that by this construction it is a very simple matter to form the angling ends 46 so that they will form a metal to metal contact with the contact bars 19 and 23; whereas if the individual leaves of the brushes are bent in order to secure the proper contacting face, as is sometimes done, it is quite difficult to form the leaves properly.

The operation of the switch is easily understandable from Figures 7, 8 and 9. Fig-

ure 7 shows the switch wide open, Figure 8 shows the lever in the closed position, while Figure 9 shows the lever in a position just prior to the release of the switch, which will permit an extremely rapid breaking of the contacts therein.

It will be noted in Figure 10 that the leaf 47 which carries the arcing point 48, is somewhat bent when the switch is completely closed. In other words—when the switch is open whatever arcing occurs will be at the heavy arcing point 48, which is well able to stand same.

While reference is made to a pair of brushes and a pair of channels in which the brushes lie, it must be understood that it is equally applicable to a one, three or more pole switch, and the two pole type has been selected for illustration merely because it is used in the greatest numbers.

It can be seen from above construction that there has been evolved a switch which can be classified as an externally operated switch wherein the operating handle is outside of the enclosing case and all of the parts comprising the circuit are enclosed under the metal cover.

I am aware that many forms of switches have been constructed in the past; it is therefore not my intention to cover such devices broadly, but I do intend to cover all such forms and modifications thereof as fall fairly within the appended claims.

I claim:

1. A molded base for brush contact switches consisting of a rectangular base plate having three parallel walls formed thereon forming a pair of adjacent channels, each of said channels having fuse terminals at one end and brush contact bars at the opposite end thereof, and having a transverse partition connecting the outer and inner partition between said fuse terminals and said brush contact bars.

2. A brush contact switch operating mechanism consisting of a cover plate, a U-shaped bracket mounted on the under side of said cover plate having a pair of guide rods mounted therein extending through said cover plate, a contact holder within said bracket having a slide on its outer end adapted to ride on said guide rods and having a plurality of rods on its lower end guiding in the bottom of said bracket and projecting therethrough, brush members mounted on opposite pairs of guide rods, a spring normally holding said brushes toward said cover plate, and a toggle mechanism for moving said brushes toward a switch-closing position.

3. A switch having in combination a double channel molded base, a pair of spaced brush contact bars mounted in each channel having the adjacent ends thereof turned downwardly into said channels, a brush be-

5 tween each pair of contact bar ends, spring means for urging both brushes out of contact with their bars, a double guide for each brush, a slide between each double guide connected to its respective brush, and a toggle lever mechanism for operating said brushes in a manner to bridge said contacts by a relatively large movement of the toggle mechanism and to release said brushes to the action 10 of said spring under a relatively small movement of said toggle mechanism.

4. A brush contact switch operating mechanism having in combination a cover plate, a channel-shaped standard mounted on said 15 cover plate having a pair of outwardly turned ears mounted thereon, a hand operating one end thereof attached to said toggle operating arm mounted on the same pivot with said hand lever, a bell crank lever having one end thereof attached to said toggle operating arm and the other end thereof forming a stop, a slide attached to said bell crank lever, said slide having a plurality of contact holder rods attached thereto, a channel-shaped bracket having holes formed 20 therein to receive said contact holder rods, a spring between said bracket and said slide, and contact brushes attached to said contact holder rods.
